UNITED STATES PATENT OFFICE.

NELLIE FORSMAN MANSURE, OF CHICAGO, ILLINOIS.

TELEPHONE-RECEIVER SUPPORT.

1,418,820.

Specification of Letters Patent. Patented June 6, 1922.

Application filed April 1, 1920. Serial No. 370,583.

To all whom it may concern:

Be it known that I, NELLIE FORSMAN MANSURE, a citizen of the United States, residing at Chicago, in the county of Cook and State of Illinois, have invented a new and useful Improvement in Telephone-Receiver Supports, of which the following is a specification.

This invention relates particularly to an attachment for telephones, which is adapted to support the receiver while the telephone is in use.

The primary object of the invention is to provide for use in connection with telephones a receiver-supporting device which will relieve the telephone user from the fatigue incident to holding the receiver while carrying on a telephone conversation. The invention has the further advantage that it enables the hands of the user to remain free during the use of the telephone.

The invention is illustrated, in its preferred embodiment, in the accompanying drawing, in which—

25 Figure 1 represents a perspective view of a telephone equipped with the improved device, the view illustrating the manner in which the receiver is supported by the attachment; Figure 2, a plan view of the attaching bracket and the counter-weight, which may serve also as a handle for the telephone; and Figure 3, a sectional view taken as indicated at line 3—3 of Fig. 1.

In the illustration given, A represents a 35 telephone of ordinary construction, having a base A¹, a standard A², a transmitter A³, a switch-arm A⁴, and a receiver A⁵; and B represents the improved receiver-support mounted on the standard of the telephone.

40 The device B, in the form illustrated, comprises a mounting ring, or clamp, B', which embraces the standard of the telephone; a counter-weight B², which may serve also as a handle for the phone; a swinging arm B³ mounted on the member B'; and a receiver-supporting clip B⁴ mounted on the arm B³.

The ring B', in the form illustrated, comprises a pair of spring jaws adapted to clasp the standard A². This may be applied by 50 forcing the jaws over the standard in an obvious manner.

It is desirable that the receiver-supporting arm B³ shall have vertical swivel con-

nexion with the telephone standard. In the illustration given, this is accomplished by 55 providing the arm with a vertical swivel-portion 1, which extends through a bearing 1^a with which the member B' is provided at its junction with the member B². The swivel-portion 1 is provided with a collar 1^b, 60 which rests upon the upper end of the bearing and said swivel-portion has its lower end provided with a thread upon which is screwed a nut 1^c. By this means the swivel connection may be made as tight as desired, 65 to provide sufficient friction so that the arm B will remain in any position of adjustment. The outer end of the arm B³ extends at a distance from the telephone standard which is considerably greater than the distance 70 which the switch arm A⁴ projects from the standard; and said outer end is equipped with a flattened perforate portion 2 which serves as a bearing for a clamping screw 3, 75 by means of which a clip 4 is secured to the arm. The clip 4 has two ears which embrace the flattened pivotal portion 2 of the arm B³, so that the portion 2 will be clamped between said ears when the screw 3 is tightened. The clip 4 has a flat upper surface 80 upon which rests the bearing 5 of a receiver-supporting spring clip 5^a. This clip is secured to the clip 4 by a rivet 6 which affords a vertical swivel connection. Thus, the clip 5^a is adapted to support the telephone 85 receiver A⁵ in substantially a horizontal position; and when the receiver is in position in the holder-clip, it may be swung in a horizontal plane about the vertical swivel connection 6. If it be desired to adjust the inclination of the receiver, this may be done 90 by means of the clamping bolt 3.

It is preferred to have the arm B extend across in front of the telephone standard, the swivel-portion 1 being thus located on 95 one side of the standard, while the receiver-supporting clip 5^a is disposed at the opposite side of the standard. However, if desired, any swivel connection between the arm B³ and the telephone standard may be employed.

The manner of use of the improved device will be readily understood. If a prolonged conversation is to be carried on, the receiver, after removal from the switch-arm A⁴, may 105 be placed in the clip 5^a, and the arm B³ may

be swung to bring the receiver into proper relation with the ear of the user while the lips of the user are in position to speak into the transmitter A³. After concluding the 5 conversation, the receiver may be removed from the clip 5^a and re-placed upon the switch arm.

The construction illustrated is simple, convenient, and well adapted to the purpose intended. The construction may be varied, 10 however, without departure from the invention.

The foregoing detailed description has 15 been given for clearness of understanding only, and no unnecessary limitation should be understood therefrom, but the appended claim should be construed as broadly as permissible, in view of the prior art.

What I regard as new and desire to secure by Letters Patent, is:

The combination with the vertical standard of a telephone, of a clamping device engaging said standard and equipped with a counterweight in the form of a handle, an arm having a vertical swivel portion journaled at the junction of said clamp and handle and having a curved portion extending across the telephone stand and provided with an upstanding extremity affording a pivot-eye, a connecting-member connected by a horizontal pivot with said pivot-eye, and a receiver-holding clip mounted on and having vertical swivel connection with said connecting-member.
